ELECTRIC SWITCH

Herschel C. Bolley, Bronson, Mich., assignor to
 H. A. Douglas Mfg. Co., Bronson, Mich., a corporation of Michigan

Application February 24, 1943, Serial No. 476,981

4 Claims. (Cl. 200—6)

1

This invention relates generally to electrical switches and, more particularly, to switches adapted for use on automotive vehicles and gun mounts in connection with ordnance equipment.

One particular object of the invention is to provide a switch in which the mechanism thereof, including the switch and casing therefor, are substantially sealed within a housing so that the switch is protected from injury and foreign matter and fluid are substantially prevented from entering and interfering with the operation of the switch.

Another object is to provide improved means for permanently securing a switch casing within a housing and preventing rotation between the two.

A further object is to provide improved means for locking the operation means for the switch in place.

Other objects and advantages of the invention will be apparent after considering the description hereinafter set forth in connection with the drawing annexed hereto.

In the drawing:

Figure 1 is a vertical section taken through the switch, the housing, means for connecting the two together, and other means whereby to clearly illustrate certain details of construction;

Figure 2 is a transverse section taken substantially on line 2—2 of Figure 1, portions of which are broken away whereby to better illustrate certain parts of the switch;

Figure 3 is a section more or less corresponding to the section shown in Figure 2, showing the switch in a position different from that illustrated in Figure 2;

Figure 4 is a bottom view of the switch and the housing with the cover removed from the latter; and

Figure 5 is a view showing the manner in which the conduits entering the housing for the switch casing are substantially sealed in place.

As noted above, one object of the invention is to provide a more or less fluid type enclosure for an electric switch and this has been found necessary because it has been found that salt water and dust have a deteriorating effect upon the operation of the switch when used on vehicles in combat zones around salt water and in desert areas. The principles of design and construction embodied in the present switch have proven very successful in actual combat zones and areas.

The housing 1 provides an enclosure for the switch casing 2 and, the housing and casing are preferably permanently secured together by a

5

tubular element 3. The housing 1 is fashioned to take the shape of a cup and is constructed of sheet metal. The switch casing 2 is also constructed of sheet metal and is similar in shape but of a size to fit concentrically and entirely within the confines of the housing 1. The switch casing 2 may be provided with any desirable means for making and breaking an electric circuit.

10 As herein illustrated the open end of the casing is preferably closed off by a composite contact carrier assembly 4, which is fixed in place by deforming fingers provided on the casing 2 over and upon the outer surface of the carrier assembly 4. The carrier assembly 4 may be provided with a plurality of rivet contact means 5, the inner extremities of which provide contact surfaces and the outer extremities of which are flanged over and upon the base portions of terminal posts 6 as clearly illustrated in Figure 1.

15 The switch mechanism within the casing 2 includes actuated means 7 supporting a bridge carrier 8. The bridge carrier 8 is held against rotation with respect to the actuating means 7 by means of tongues provided on the actuating means which project into suitable notches provided therefor in the periphery of the carrier. The carrier 8 is preferably provided with a pair of spaced apart bridge means 9 and 10 which are secured for movement with the carrier 8 by means of lugs provided on the bridge means which project through suitable apertures provided therefor in the carrier as illustrated in Figures 1 through 3. Each of the bridge means 9 and 10 is preferably provided with a pair of rounded bosses forming contacts which are adapted to cooperate with the various rivet contact means 5 in the manner desired to control certain electrical circuits.

20 The bridge means 9 and 10 carried by the carrier 8 are urged rearwardly toward the contact carrier assembly means 4 and the actuated means 7 forwardly in an opposite direction by means of a helical spring 11. As clearly shown one extremity of the spring bears against the carrier 8 and the opposite extremity receives an inwardly extending centrally disposed boss portion provided in the base of the actuated means 7 whereby to hold the spring in a predetermined position so that the energy exerted thereby is properly distributed to provide a well-balanced construction. It will be noted that the arrangement is such that the spring cannot engage the lugs provided on the bridge means 9 and 10 which project through the carrier 8.

2

Means are provided for predetermining the "on" and "off" positions of the actuated means and means associated therewith with respect to the rivet contacts 5. The positioning as herein shown is preferably accomplished by providing the base of the actuated means 7 with a plurality of depressions or seats 13, certain of which are illustrated in Figure 1. The base or end wall of the switch casing 2 is provided with a plurality of inwardly extending detents 12 which are adapted to cooperate with the seats 13 in the desired manner. It will be noted that the seats 13 and detents 12 are so constructed and arranged that the base of the actuated means 7 and the end wall of the switch casing 2 are held in spaced apart parallel relation so as to alleviate friction.

The operating means of the switch includes a relatively short shaft 14 which is rotatably mounted in the bore 15 of the tubular element 3. The inner extremity of the shaft is connected to the actuated means 7 in any desirable manner, but as herein illustrated, the shaft is provided with a tongue portion 16 which projects into a rectangular aperture 17 provided in the base of the centrally disposed boss portion of the means 7. It will be noted that the inner extremity of the tubular element 3 is provided with a tubular portion 18 which extends through apertures 19 and 20 provided in the end walls of the housing and casing and is flanged over and upon the inner surface of the end wall of the casing 2 for permanently securing the housing, casing, and tubular element in assembly. The casing 2 is held against rotary movement with respect to the housing 1, by providing the end wall of the housing with an inwardly extending projection 21 which fits into a hole or recess 22 provided in the end wall of the casing 2.

The switch may be mounted as desired, but is preferably adapted to be secured to the rear side of an instrument panel mounting so that the threaded portion of the tubular element projects forwardly through a suitable aperture provided therefor in the mounting with the shoulder 23 of the element engaging the rear side of the mounting and so that a nut which cooperates with the threads on the element engages the front side of the mounting.

Means are provided whereby to prevent dust, dirt or other foreign matter from entering the housing and switch casing through the tubular element 3 and this is accomplished by providing the outer extremity of the tubular element 3 with annular recesses 24, 25 and 26, the diameters of which progressively decrease in the order named. The recess 26 slidably receives a cylindrical enlargement 27 provided on the shaft 14 whereby to limit inward movement of the shaft. A fiber washer 28 or the equivalent is disposed in the recess 25 between the recesses 24 and 26 and is pressed into place by a washer 29, the latter of which is secured in position by flanging over some metal of the element upon the washer. The washer is compressed to such an extent that portions thereof are forced into intimate engagement with the walls of the recess 25 and the cylindrical surface of the shaft 14 including a side of the enlargement 27. This arrangement, in addition to excluding foreign matter, provides means for holding the shaft against outward movement. Obviously, if found desirable the washer 28 may be impregnated with graphite or other desirable lubricant.

The recess 24 provides clearance so that a key, screw driver, or the equivalent, may enter the notch 30 provided adjacent the outer extremity

of the shaft 14. A pivotal cover conceals the shaft 14 and provides additional means for excluding foreign matter from entering the switch and housing. The cover may be provided with a raised portion 31 whereby to facilitate pivotal movement of the cover.

To operate the switch, it is merely necessary to insert a key into the operating means or shaft 14 and rotate same including the actuated means 10 one way or the other so that the bridge means 9 and 10 will cooperate with the rivet contacts 5 in the desired manner to control the various electrical circuits. No reference is made as to which rivet contacts are engaged by the bridge means 9 and 10 for the reason that the invention is not directed to the contacts, bridge means or circuits controlled thereby.

Additional means are provided whereby to prevent fluid and foreign matter from entering the switch housing and switch casing and will now be described. The free extremity of the switch housing 1 is preferably provided with a radially extending flange 32 which is provided with a plurality, preferably three, equally spaced apart apertures 33. The open end of the housing 1 is closed off by an annular cover 34. A rubber washer 35 or the equivalent is disposed between the flange 32 and that portion of the cover opposite the flange 32. Clamping bolts 36 pass through apertures provided therefor in the cover and washer and through the apertures 33 in the flange 32 whereby to seal off the open end of the housing. This arrangement provides a shield or guard for the switch casing, including the take-off terminals 6, and at the same time provides a substantially fluid-tight enclosure for the switch casing.

The conductor wires or leads which are adapted to be connected to the take-off terminals 6 are preferably encased in conduits which are adapted to enter the side wall of the housing 1. One of the conduits 37 is illustrated in Figure 5. The side wall of the housing is provided with a pair of closely related apertures, and rubber grommets 38 or the equivalent are secured in the apertures. Each grommet is so constructed that it may be pressed and held in place by its own resiliency with portions engaging the opposite surfaces of the side wall of the housing. Each conduit is preferably of a slightly greater outside diameter than the inside diameter of the hole in each grommet as illustrated in Figure 5 so that the grommet will resiliently bear against the conduit, and other portions will be pressed tightly into engagement with portions of the side wall of the housing so as to provide a connection which will prevent fluid or foreign matter from entering the housing through the apertures in the side wall of the housing or through the holes in the grommets.

In view of the foregoing, it will be apparent that a plurality of improved means have been provided whereby to protect an electric switch from injury resulting from impact and other harmful effects.

Having thus described my invention, it is obvious that various modifications may be made in the same without departing from the spirit of the invention; and, therefore, I do not wish to be understood as limiting myself to the exact form construction, arrangement, and combination of parts, herein shown and described.

I claim:

1. Electric switch construction including, an electric switch casing containing conventional

switch mechanism, said switch casing having an end wall, a housing enclosing the said electric switch casing and switch mechanism, said housing having an end wall, aligned apertures provided in the end walls of said switch casing and said housing, means passing through said apertures for firmly securing said casing and the housing together, cooperating means provided on one of the end walls, and means provided on one of the other end walls interengaging said cooperating means whereby to prevent rotation of said housing in respect to said switch casing.

2. An electric switch construction including, an open ended housing having an end wall, an electric switch disposed in said housing, said switch being provided with a casing having an end wall engaging the end wall of the housing, apertures provided in the said end walls, and tubular bearing means, said bearing means being provided with a reduced extremity projecting through the said apertures and with its end flanged over and against the inner wall of the switch casing for permanently securing the housing, casing, and bearing together.

3. Electric switch construction including, an electric switch casing containing conventional switch mechanism, said switch casing having an end wall, a housing receiving said switch casing and switch mechanism, said housing having an

end wall, aligned apertures provided in the end walls of said switch casing and said housing, means passing through said apertures for firmly securing said casing and housing together, a pocket provided in the end wall of said casing, and means projecting into the pocket from the end wall of the housing whereby to prevent rotation of said casing with respect to said switch housing.

- 10 4. An electric switch construction including; an open ended housing having an end wall, an electric switch disposed centrally in said housing; said switch being provided with a casing having an end wall engaging the end wall of the housing; apertures provided in said end walls; tubular bearing means having a reduced inner extremity projecting through the apertures and with its end flanged over and against the inner wall of the switch casing for permanently securing the housing, casing, and bearing together; means on one of said end walls cooperating with means on the other end wall preventing rotation of said casing with respect to said housing; means for closing and sealing the open end of said housing; means for closing off an outer extremity of the tubular bearing; and means providing a seal seated in said bearing adapted to engage shaft means movable in said bearing.
